COMBINATION DRIER AND CLEANER

Dewey D. Day, Dallas, Tex., assignor to The Murray Company, Dallas, Tex.

Application March 19, 1945, Serial No. 583,616

14 Claims. (Cl. 19—93)

1

This invention relates to new and useful improvements in combination driers and cleaners.

One object of the invention is to provide an improved combination drier and cleaner especially adapted for handling fibrous materials, such as seed cotton and particularly arranged for conditioning machine-picked cotton.

A particular object of the invention is to provide an improved drier and cleaner involving a circuitous travel path for the seed cotton, whereby the damp or wet cotton is caused to move in reverse courses while being motivated by a stream of heated air and subjected to an efficient cleaning action at the end of each course.

A further object of the invention is to provide a preliminary drying area wherein the progressively moving cotton is carried through an elongate circuitous path by a stream of heated air to partially dry it before carrying it through the cleaning area of the apparatus.

Another object of the invention is to provide an apparatus of the character described wherein a plurality of cleaning cylinders are vertically disposed at each side of the apparatus and the seed cotton traveling in a circuitous path between these groups of cylinders, is carried over cleaning surfaces beyond which surfaces, air escapes are provided to more efficiently remove dust, fine trash and foreign matter from the cotton.

An important object of the invention is to provide a combined drier and cleaner, wherein the fibrous material moves in reverse transverse paths, while being motivated by the heated air stream, such paths each being of substantial length; together with revolving fan-type cylinders which set up sufficient centrifugal force to maintain a speed of travel of the cotton adequate to prevent choking as well as to obtain effective drying and at the same time permitting a sizeable proportion of the air stream to be exhausted through the cleaning screens.

A particular object of the invention is to provide a combined drier and cleaner wherein a plurality of fan-type revolving cleaning cylinders are correlated with cotton conductor shelves in such a manner that each cylinder after receiving the cotton from an intermediate shelf and carrying it downwardly over a cleaning surface, casts the cleaned cotton onto a lower shelf without again carrying said cotton onto the cleaning surface or repeating the revolving cycle of said cotton, whereby machining or injury to the cotton fibers is substantially eliminated and a positive discharge of all of the cotton from each cleaning area is obtained.

2

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a perspective view of a combined drier and cleaner apparatus constructed in accordance with the invention.

Fig. 2 is a longitudinal, vertical, sectional view of the drier and cleaner.

Fig. 3 is a detailed view of one of the adjustable deflectors.

Fig. 4 is a partial longitudinal, sectional view of a modified form of drier and cleaner.

Fig. 5 is a detailed view of one of the cleaning grates and its correlated cylinder, partly in perspective and partly in section.

Fig. 6 is a transverse, sectional view through one of the grates, and

Fig. 7 is a view partly in elevation and partly in section showing a cotton by-passing arrangement.

In the drawings, the letter A designates the combined drier and cleaner proper. In Fig. 1, the drier and cleaner is shown as connected by a flared, transverse, feed duct B, with a cross-blow box C. Seed cotton is conveyed by air suction from a suitable source, into an air and cotton separator D of the usual type, the air currents passing off and the seed cotton being dropped into the blow box by the ordinary revolving gate E. The blow box has an inlet C' to which a conductor (not shown) may be connected for blowing a stream of heated air into and across said box, whereby the falling cotton is carried into the duct B and conducted upwardly to the top of the drier and cleaner A.

The bottom of the blow box opens into a bypass hopper F which has a chute G leading down to the lower portion of the apparatus A and a divergent chute H leading down to a vacuum hood I connected at one side to the discharge end of the drier and cleaner A. The hood has an open bottom resting upon the top of an ordinary gin distributor J. At the juncture of the chutes G and H, a by-pass valve F' is pivoted and may be swung to divert the cotton into either chute. The current of the cross stream of heated air flowing through the box C will be strong enough to carry all of the falling cotton into the duct B; however, a suitable cut-off valve E' may be pivoted in the box below the duct. By the foregoing

arrangement, the cotton may be carried through the drier and cleaner, or the cross stream of air may be cut off and the valve F'' swung to close off the chute H , whereby the cotton is delivered to a transverse cleaner unit A' at the bottom of the unit A . If desired, the valve F'' may be swung to close off the chute G and the cotton discharged directly into the vacuum hood I and the distributor J .

Also in the drawings, the numeral 10 designates the vertical casing of the drier and cleaner, the upper portion of which is reduced in width and forms a preliminary drying chamber or compartment 11 . This casing has upright side walls 16 and 17 , respectively, and front and back walls 18 and 19 , respectively. At each side of the casing, upright cleaning ducts or flues 12 are formed. The casing 10 opens into and is supported upon an elongate transverse cleaner housing 13 forming part of the unit A' . The housing 13 opens into a transition 14 which is connected to a flue 15 for carrying off the cleanings from the housing 13 .

The duct B , which is flared upwardly discharges into one side (right side Fig. 2) of the preliminary drying compartment 11 . This duct extends substantially from the front wall 18 to the back wall 19 of the casing and delivers the heated air and cotton in a relatively broad, flat stream. A plurality of flat horizontal shelves 20 , 21 and 22 are suitably supported in the compartment 11 . The shelf 20 extends from the inlet toward the opposite side of the compartment. A transverse curved deflector 23 extends from the shelf 21 up to the inclined top 24 of the compartment and is spaced from the end of the shelf 20 a sufficient distance to allow a free downward flow and discharge, of the air and cotton stream. The downwardly inclined top 24 aids in diverting the air and cotton stream onto the deflector. The inner end of the shelf 20 overhangs the shelf 21 which latter terminates short of the upright right hand side wall of said compartment. This shelf 21 overhangs the shelf 22 which terminates short of the left hand side of said compartment. The shelf has an inclined section 25 at one end which abuts the transverse apex of a triangular deflector 26 , onto which the cotton from the shelf 21 is discharged.

The seed cotton is carried into the compartment 11 by the stream of heated air. This stream is heated by suitable means before it is blown into the box C and its temperature may be varied in accordance with the moisture content of the cotton. The air and cotton stream travels back and forth transversely of the compartment through the channels formed by the shelves 20 , 21 and 22 , and the cotton, while being carried through this elongated circuitous path is subjected to a preliminary drying. Some initial drying of the cotton takes place in the duct B , but the drying accomplished in the compartment is more effective.

The casing 10 is provided with an upper horizontal shelf 27 , a lower horizontal shelf 28 and intermediate horizontal shelves 29 , all suitably spaced apart and disposed in staggered and overhanging relation, whereby the cotton may be discharged from one shelf onto the next lower shelf and carried by, and with the heated air stream, in a sinuous or circuitous path through the drier; the shelves forming reverse channels therebetween.

The cleaning flues 12 at the side of the casing are defined by the side walls 16 and 17 , the front wall 18 , the rear wall 19 and a plurality of vertical

cleaning screens 30 . Each screen 30 is curved in a vertical arc concentric to the longitudinal axis of a correlated revolving cylinder 31 . The upper and lower ends of each screen abut the ends of alternate shelves, with an intermediate shelf terminating approximately in alignment with the transverse axis of the correlated cylinder. The ends of the shelves which terminate opposite the cylinders may each have an upwardly inclined transverse guide section 32 for the purpose of discharging the cotton on top of the cylinder. The cylinders are suitably driven (not shown) to revolve away from the guide sections; those at the right hand side of Fig. 2, revolving clockwise and those at the opposite side, revolving counter-clockwise.

Each cylinder is of the fan-type which is in common use in this art. Such cylinders not only carry the cotton over the screens 30 , but create a fan blast which is discharged with the cleaned cotton along the underlying shelves. This is an important feature of the invention because it supplies a motivating force which propels the cotton toward the cylinder at the opposite end of the shelf and prevents choking in the channels between the shelves. The longitudinal blade portions 33 of each cylinder are provided with spaced stub pins or prongs 34 , directed outwardly and radially of the cylinder.

The cylinders are mounted so that the prongs sweep downwardly in close proximity to the arcuate surfaces of the screens 30 . By discharging the cotton on top of the cylinders it is carried downwardly and ejected onto, and blown along the underlying shelf. The prongs 34 pass in such close proximity to the upper edges of the guide sections 32 as to prevent the cotton being carried upwardly therebeyond, thus the carrying of cotton around with the cylinder is substantially defeated.

The particular structure of the screens is subject to considerable variation. While the screens 30 are shown as of the mesh type in Fig. 2, it is to be understood that any foraminous or grate-type of screen may be used. Under the character of machine cotton picking, as done at the date of this application, more satisfactory results have been obtained by using the grate-type of screen. In Figs. 4, 5 and 6, I have illustrated generally a grate-type of screen which includes a plurality of longitudinal spaced shafts 35 , each having closely spaced arcuate fingers 36 extending therefrom and forming a grate surface. Each shaft has an adjusting arm 37 fastened to each end thereof and provided with a curved slot 38 , through which fastening bolts 39 pass. The bolts are mounted on the front and back walls 18 and 19 , respectively.

In order that effective cleaning may be accomplished, a proportionate amount of air is caused to pass through the screens 30 and exhausted through the flues 12 . The air currents in passing through the screens carry the cleanings into the flues. Angular aprons 40 are mounted transversely in the flues with their skirts 41 in engagement with the lower longitudinal portions of the screens. The lower edges of the skirts are secured to transverse angular rails 42 to which the adjacent edges of the screens are also attached; said rails being located at the ends of certain of the shelves 28 and 29 . The skirts 41 close off the lower portions of the screens so that trash and dust forming the cleanings, are caused to fall on the inclined aprons 40 when carried into the flues.

The cleanings slide down the aprons onto de-

fectors 43, adjustably mounted, at their ends on the front and back walls of the casing. The lower transverse edges of these deflectors are correlated with the end walls 16 and 17 of the casing to provide adjustable passages for downward flow of the air currents and cleanings, whereby the volume and flow of air through the screens is controlled. Windows 44 are provided in the front and back walls of the casing above each deflector, through which the cleaning operation may be observed.

At the lower end of the right hand flue 12 (Fig. 2), the deflector 43' is mounted in reverse relation to the deflector thereabove so as to deflect the cleanings into a transverse screw conveyer 45 which discharges at its rear end into a flue 46. The flue 12 at the left hand side of the casing (Fig. 2) opens at its lower end into a transverse trunk 47 as is shown in Fig. 1. This trunk discharges into a transition 48 from which a flue 49 extends. The flues 46 and 49 may be connected at a suitable point to the flue 15, if desired. The cleanings and air currents will pass directly down into the trunk 47 and thus, a conveyer is not required at this side of the apparatus.

The horizontal cleaner A' which is connected to the lower end of the casing 10 may be of any suitable type. The cleaner housing 13 extends from the side of the casing 10 under the conveyer 45 and the extension is covered by a top plate 50, into which the chute G is connected. A plurality of fan-type cylinders 51, similar to the cylinders 31, are mounted in the housing and revolve in a counter-clockwise direction. Arcuate screens 52 of the same type as the screens 30, are mounted under the cylinders across the housing. Cotton discharged from the lowermost cylinder 36 (Fig. 2) is cast thereby under the shelf 28 and falls upon the cylinders 51; also, some of the cotton will fall directly into the cylinder 51, under such lowermost cylinder 31. This cotton, which has been partially cleaned by the cylinders 31 and screens 30, will be carried through the cleaner A' and thoroughly cleaned.

The housing 13 is connected to, and discharges into a gate casing 53 at one side of the vacuum hood I. A revolving gate 54 carries the cotton into the hood. The gate revolves in a clockwise direction and prevents the air pressure in the cleaner A' from escaping into the hood.

In operation the seed cotton supplied from a suitable source to the separator D, is dropped by the revolving gate E into the cross-blow box C. A stream of air heated to the proper temperature is directed across the box through the inlet C', and supplied in any suitable manner. The particular temperature to which the air is heated depends upon the dampness or wetness of the cotton and such air may be warm or hot. Temperatures ranging from atmospheric to 250° F. have been used satisfactorily.

The stream of heated air is blown into the box C with sufficient force to carry the cotton into and upwardly through the duct B and thence through the compartment 11. The cotton, partly in suspension and otherwise motivated by the air stream is given a preliminary drying. This drying action is accentuated in the compartment where the cotton is carried back and forth through the elongate reverse channels or path formed by the shelves 20, 21 and 22.

The cotton leaving the shelf 22 is carried along the shelf 27 and through a channel formed between said shelves 22 and 27. As the cotton approaches the uppermost cylinder 31, it is de-

flected or guided onto the top of said cylinder by the inclined section 32 at the adjacent end of said shelf. The pins 34 carry the cotton down over the surface of the screen 30, whereby the cotton is partially cleaned; loose particles and dust being removed. A portion of the air stream passes through the screen, according to the adjustment of the uppermost deflector 43, thus more effectively cleaning the cotton and carrying off the cleanings.

The cotton is then swept down onto the uppermost shelf 29. Owing to the closure of the lower portion of the screen 30 by the skirt 41, the escape of air therethrough is substantially cut off which releases the cotton from the surface of the screen and permits it to be freely carried onto the shelf 29 by the cylinder. By reason of the foregoing and the proximity of the guide section 32 to the circular path of the pins 34, as well as the location of said section with respect to the top and bottom of said cylinder, the cotton will not be again carried around by the cylinder. The fan-type of cylinder serves to step up the velocity of the air stream as well as to impel the cotton along the uppermost shelf 29. The force thus generated is sufficient to move the cotton and discharge it onto the cylinder 31 at the opposite end of the shelf 29. By thus motivating the cotton, choking in the channels between the shelves is prevented; also, the cotton is sufficiently agitated to hold it more or less in suspension in the heated air stream, thus intensifying the drying function.

The cotton is carried back and forth over the remaining shelves 29 and cleaned by the cylinders 31 and then discharged onto the bottom shelf 28 from which it is delivered to the lowermost cylinder 31 (Fig. 2). By the time the cotton reaches the last cylinder 31, it will be thoroughly dried, but it will still entrain some trash and dust. The cotton is finally discharged into the housing 13 of the cleaner A'. The cotton in passing through the cleaner is thoroughly cleaned, the cleanings being carried downwardly through the screens 52 by the air stream into the transition 14. The cleaner discharges the cotton onto the revolving gate 54 which casts it into the vacuum hood I.

In Fig. 4, I have shown another form of apparatus constructed in accordance with the invention. Instead of the deflectors 43, transverse revolving gates 60 are mounted in the flues 12. The longitudinal edges of the blades of each gate wipe across a transverse sealing strip 61 secured along the lower edge of the adjacent apron 40. Opposite each gate a vent opening 62 is provided in the side wall of the casing. These openings are controlled by valve plates 63, each adjustably hinged to the end wall of the casing and overhanging the inner face of said end wall.

The escape of air through the vents 62 is controlled by the valve plates. The gates 60 on the right-hand side (Fig. 4) revolve in a counter-clockwise direction, while the gates 60 on the left-hand side (Fig. 4) revolve in a clockwise direction and thus discharge the cleanings downwardly in the flues 12. The edges of the blades of the gates wiping over the strips 61 and upwardly of the inner faces of the valve plates 63, provide seals, whereby the cleanings are dropped and not carried out with the vented air currents.

In Fig. 4, the shelf construction is somewhat altered in that the intermediate shelves 29 and the bottom shelf 28 are illustrated as being disposed relatively above the centers of the cylinders 31, and thus, the inclined guide sections 32 are not required. Under each cylinder a sub-shelf

64 is provided and connected with the shelf proper by an inclined guide section 65. The blast action produced by the cylinders impels the cotton along the sub-shelves, up the guide sections onto and along the shelves, whereby it is discharged onto the cylinder at the opposite end.

The combination of the drying and cleaning elements of the apparatus not only provides more efficient drying and cleaning, but produces a higher grade of cotton, particularly where machine picked cotton is handled. Machine-picked cotton gathers an increased amount of leaf trash, stems, grass, vines and some cotton hulls. Where the cotton is damp or even wet, the cleaning problem is accentuated unless the cotton is thoroughly dried. By combining thorough drying and cleaning without "machining," twisting and undue agitation or stringing out, of the cotton fibers, not only is the cotton better prepared for ginning, but a higher priced ginned cotton is obtained. The terms used in the preceding sentence are well known in the cotton art. The feature of preventing the cleaning cylinders 31 from carrying the cotton over the screens 30, more than once, is highly beneficial as it prevents damage to the cotton fibers. Also, by utilizing the air blast of these cylinders to move the cotton along and between the shelves, not only is choking eliminated, but a more fluent flow of the heated air stream is obtained and the drying action is thus made more effective.

In Fig. 7 I have shown an arrangement for bypassing overflow cotton from the distributor J around the drier and cleaner to prevent carrying such cotton through the drier, a second time. In ginning cotton with a battery of gins, quantities of seed cotton are discharged from the open end of the distributor during each run or ginning. As such accumulations are less than a bale, each batch is carried back into the system and introduced into the separator D. A hopper K is attached to the bottom of the gate E and provided with a spout L and an inclined chute M. The spout discharges into a revolving gate N which is mounted on top of the cross-blow box C. A by-pass valve O is pivoted in the hopper at the intersection of the spout and chute to cut off either of them.

The chute M is connected to an angular trunk P which discharges into the outer side of the vacuum hood I. A yoke-shaped manifold R straddles the trunk and is connected with the inlet C' of the blow box. The manifold receives heated air from a suitable source. The chute H, hopper F and valve F' are omitted and the chute G is connected directly to the bottom of the box C.

In ordinary operation the valve O is swung to close off the chute M and the bottom of the box C is closed by the valve E'. This allows the cotton to discharge from the separator D into the gate E and flow down through the gate E through hopper K and spout L into gate N, from which it is discharged into the box C. The operation from the box C is the same as hereinbefore described.

When it is desired to by-pass overflow cotton, the valve O is shifted to close off the spout L and divert the cotton into the chute M. Owing to steep inclination of the chute M and the upright position of the trunk P, said cotton will readily slide down these conductors to the hood I, from whence it is discharged into the distributor J. By this arrangement the cotton is not

subjected to a second drying and cleaning and also, it is not necessary to close off the flow of the heated air.

If it is desired to clean cotton without drying it, the chute M is closed by the valve O and the valve E' is swung up to close off the duct B and open the bottom of the box C, whereby the cotton will pass down the chute G and be cleaned as hereinbefore described. If the heated air supply is not cut off it will pass down through the chute G with the cotton and be discharged out through the screens 52. If the heated air is cut off, then the cotton will pass down through the chute G by gravity to the cleaning cylinders 51.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A drier and cleaner including, an upright casing, means for supplying a stream of heated air and cotton to the upper portion of said casing, upright flues at each side of said casing, transverse overhanging shelves in said casing between said flues, cleaning screens between the ends of the shelves and the flues, and fan-type revolving cylinders mounted in the casing in position to carry the cotton over said screens and impel it along said shelves.

2. A drier and cleaner as set forth in claim 1, and means for exhausting a proportion of air stream through the flues.

3. A drier and cleaner including, a casing having an inlet at its upper portion for a heated air and cotton stream and an outlet at its lower portion, transverse communicating channels in the casing for conducting the air and cotton stream in a circuitous path generally downward from the inlet to the outlet, cotton cleaners at spaced vertical intervals in said path including screens and revolving cylinders, flues open to said screens, and means in said flues for controlling the discharge of air through said screens.

4. A drier and cleaner including, a casing having an air and cotton inlet at its upper end and a cotton outlet at its lower end, staggered transverse shelves disposed in the casing between the inlet and the outlet thereof forming a circuitous air and cotton path through the casing, each shelf having one free end, and fan-type revolving cylinders mounted in the casing in said path on each side of the casing opposite the free ends of the shelves, whereby cotton is received upon each cylinder and discharged thereby onto an underlying shelf.

5. A drier and cleaner as set forth in claim 4, and an upright cotton cleaning screen contiguous to each cylinder.

6. A drier and cleaner including, a casing having an air and cotton inlet at its upper end and a cotton outlet at its lower end, staggered transverse shelves disposed in the casing between the inlet and the outlet thereof forming a circuitous air and cotton path through the casing, and separate cleaning compartments at the ends of the shelves on opposite sides of the casing, each compartment having an upright cleaning screen and a fan-type cylinder revolving therein for cleaning cotton and impelling cotton along said shelves.

7. A drier and cleaner including, an upright

casing having means for admitting a heated air and cotton stream, a preliminary drying compartment in the upper portion of the casing receiving the air and cotton stream having means for conducting the stream therein through a transversely elongated path, a circuitous conductor extending downwardly in the casing from the compartment and including impervious partitions and upright cleaning surfaces connecting the ends of some of the partitions, and fan type cylinders at opposite sides of the casing between some of the partitions and co-acting with the cleaning surfaces.

8. A drier and cleaner including, a casing having an inlet at its upper end for admitting a heated air and cotton stream and air and cotton outlets, a plurality of vertically spaced transverse shelves, certain of the shelves overhanging at one side of the casing and the intermediate shelves overhanging at the opposite of the side of said casing, fan-type cylinders between the overhanging ends of the shelves, cleaning surfaces between the overhanging ends of the shelves contiguous the cylinders, the ends of shelves intermediate the overhanging shelf ends terminating opposite said cylinders.

9. A drier and cleaner as set forth in claim 8, and air exhaust flues connected with the cleaning surfaces.

10. A drier and cleaner as set forth in claim 8, and means at the ends of intermediate shelves opposite the cylinders for discharging cotton on top of said cylinders.

11. A drier and cleaner as set forth in claim 8, wherein the ends of the shelves which terminate opposite the cylinders are each in such proximity thereto as to strip cotton from a cylinder.

12. A drier and cleaner including; an upright

casing having a heated air and cotton stream inlet at its upper end; means for conducting said stream downwardly in the casing in a circuitous path comprising, elongate impervious partitions spaced one above the other having their ends staggered at each side of the casing, and upright cleaning surfaces connecting the overhanging ends of some of the partitions at each side of the casing; and fan type revolving cylinders between the overhanging ends of some of the partitions at each side of the casing coating with the cleaning surfaces.

13. A drier as set forth in claim 12, and air exhaust means at the cleaning surfaces.

14. A drier as set forth in claim 12 wherein the ends of some of the partitions between the overhanging partition ends are opposite the medial portions of the cylinders for delivering cotton onto the upper portions of said cylinders.
